[57]

ABSTRACT

An automatic fluid dispensing apparatus for measuring and dispensing preselected quantities of a fluid. Upon selection of the desired dispensing quantity the apparatus is activated for automatically discharging substantially the exact amount of the fluid, thus providing substantially equal results with each similar selected operation. The quantity of the fluid delivered is accurately counted whereby an inventory of the fluid may be maintained at all times.

AUTOMATIC FLUID DISPENSING APPARATUS

This invention relates to improvements in a fluid dispensing apparatus and more particularly, but not by way of limitation to an automatic dispensing and measuring apparatus for fluids wherein a preselected quantity of the fluid is automatically dispensed.

Franchise food establishments are widespread today, and it is most desirable to maintain a constant quality for the food stuffs available at similar establishments wherever they may be located. Accordingly, each establishment is normally provided with particularly designed or selected equipment in order to establish a common result in each eating place. By way of example, there are many pizza establishments throughout the country, and each chain of operations endeavors to establish a common quality for pizzas available at each of the establishments bearing the name of the chain. Whereas most of the ingredients and the particular cooking and serving procedures may be accurately coordinated and controlled, the application of the pizza sauce on the various size pizzas varies considerably since this is usually a hand dip operation and depends upon the manual handling thereof by the cook or operator. In order to establish a more uniform result, it is important to assure a substantially exact quantity of the pizza sauce for each size pizza, and this is very difficult to achieve with the common hand dip method.

The present invention contemplates a novel automatic dispensing apparatus particularly designed and constructed for delivering a preselected quantity of pizza sauce in accordance with the particular size pizza requiring the sauce. The operation or dispensing of the sauce is repeated time after time with substantially no variation from the desired preselected quantity, thus assuring a constant and uniform application of sauce for pizzas in each of the food establishments requiring the service. The novel device comprises a sauce retaining chamber having an agitator therein for assuring a substantially homogeneous mixture for the sauce throughout the operation of the device. The sauce is delivered to the dispensing spout or nozzle by a pumping apparatus which is activated by a plurality of switches through a timing device. Each switch activates the pump through a different time period in accordance with the particular quantity of sauce to be delivered. The timing of the pump operation results in the dispensing or delivering of a preselected quantity of the sauce which is established or determined in accordance with the size of the pizza upon which the sauce is to be deposited. In addition, a float is provided in the sauce chamber for limiting use of the pump when the supply of sauce drops below a predetermined level. Of course, the sauce supply may be replenished for restoring the normal operating conditions for the apparatus. In addition, a control device generally similar to that disclosed in co-pending application Ser. No. 784,070, filed Dec. 16, 1968, and now U.S. Pat. No. 3,608,778 entitled "Automatic Fluid Dispensing Apparatus" and of which I am a co-inventor, is utilized in conjunction with the novel dispensing apparatus for facilitating the control thereof and for maintaining an accurate count of the quantity of sauce delivered by the apparatus.

It is an important object of this invention to provide a novel apparatus particularly designed and constructed for automatically dispensing a preselected quantity of fluid with repeated accuracy.

It is another object of this invention to provide a novel apparatus for automatically dispensing pizza sauce in preselected quantities in a manner providing uniformity of quality in the making of pizzas.

Another object of this invention is to provide a novel fluid dispensing device for delivering pizza sauce in variable preselected quantities in accordance with the pizza size with repeated uniform delivery for each selected quantity.

A still further object of this invention is to provide a novel automatic fluid dispensing device wherein an accurate measurement of the quantity of fluid dispensed is maintained for facilitating inventory recording of the fluid.

Other and further objects and advantageous features of the present invention will hereinafter more fully appear in connection with a detailed description of the drawings in which:

FIG. 1 is an elevational view of a power supply unit utilized in the invention.

FIG. 2 is a sectional view partly in elevation of a dispensing apparatus embodying the invention with portions depicted in dotted lines for purposes of illustration.

FIG. 3 is a schematic view of an electrical circuit of the invention.

Referring to the drawings in detail, reference character 10 generally indicates a dispensing apparatus comprising housing 12 constructed of any suitable material, and preferably of a material approved by the Federal Food and Drug Administration for use in connection with foodstuffs. A removable cover 14 is provided for one end of the housing 12 for facilitating access to the interior thereof, and a support plate 16 may be removably secured within the housing 12 in any suitable manner (not shown) for a purpose as will be hereinafter set forth.

The housing 12 is preferably disposed or mounted on a suitable support member 18 having an aperture 20 therein in substantial alignment with the housing 12. The support 18 may be a counter top, table, shelf, or the like, or any other type of support, as desired. A vessel or fluid container 22 is disposed below the housing 12 and aperture 20 and may be supported on a surface 24 in any well known manner. The surface 24 may be a shelf or the like disposed beneath the support member 20. For example, the support 20 may be a counter top in an eating establishment and the surface 24 may be a shelf below the counter top and accessible from the rear of the counter, as is well known in this type of establishment. A supply of pizza sauce 26 is contained within the vessel 22 for delivery or dispensing by the apparatus 10 in a manner as will be hereinafter set forth. The vessel 22 is separate and independent from the apparatus 10, and it is to be understood that the apparatus 10 may be utilized with substantially any supply of sauce or fluid.

A centrally disposed shaft 28 extends through the plate 16 and is suitably journaled therein for rotation by a suitable motor 30 which is mounted within the housing 12 and is preferably mounted on the plate 16 in any well known manner. The shaft 28 extends into the vessel 22 and terminates in the proximity in the bottom thereof as particularly shown in FIG. 2. A support bracket 32 may be secured to the housing 12 in any suitable manner and extends downwardly therefrom into the vessel 22. The bracket 32 is provided with an

aperture (not shown) for receiving the shaft 28 therethrough and facilitates stabilization of the shaft 28 during rotation thereof. A plurality of radially extending blades 34 are secured to the outer end of the shaft 28 in any well known or suitable manner (not shown) for rotating simultaneously with the shaft 28 to stir the sauce 26 for a purpose and in a manner as will be hereinafter set forth.

A pump 36 is disposed within the vessel 22 and is supported from the housing 12 by a tube or delivery pipe 38. The pump 36 may be of any suitable type and the impeller thereof (not shown) is preferably provided with two blades whereby the flow of fluid through the pump will be at a rate for providing an optimum delivery of the sauce 26 as will be hereinafter set forth. A suitable motor 40 is mounted within the housing 12 in any well known manner and preferably on the plate 16 and is operably connected with the tube 38 for operation of the pump 36 to deliver fluid from the pump 36 to a delivery tube 42 as is well known. The tube 42 is preferably constructed from quarter inch pipe, but not limited thereto. It has been found that this particular size for the delivery tube 42 in combination with the output of a two-blade pump 36 delivers approximately 30 gallons of sauce 26 per minute or one and one quarter ounce of the sauce 26 per second. This delivery rate has proven beneficial and advantageous for the dispensing of the pizza sauce 26 as will be hereinafter set forth.

A float member 44 is suspended from the housing 12 within and disposed within the vessel 22. The float 44 may be of any suitable type and as shown herein is reciprocally secured on a guide shaft 46 in any well known manner (not shown). The shaft 46 is preferably secured to the plate 16 at the proximity of a micro-switch 48 or the like whereby the float 44 activates the micro-switch 48 during reciprocation of the float 44 for a purpose as will be hereinafter set forth.

The delivery tube 42 is preferably angular or substantially U-shaped in configuration as shown in dotted lines in FIG. 2 whereby one portion 50 thereof extends through an aperture (not shown) in the housing 12 and outwardly therefrom. The outer end 52 of the tube 42 extends downwardly and is the dispensing end thereof for delivering the pizza sauce 26 or other fluid during operation of the apparatus 10. A protective cover 54 is secured to the outer periphery of the housing 12 for substantially encasing the portions 50 and 52 of the dispensing tube 42. A plurality of micro-switches, for example switches 56, 58, and 60 shown in dotted lines in FIG. 1, are mounted by a suitable support structure 62 which in turn is secured to the outer periphery of the housing 12 in the proximity of the covering 54. The switches 56, 58, and 60 are operably connected with the pump 36 in a manner as will be hereinafter set forth and are activated by trigger arms 64, 66, and 68 respectively which depend from the switches as clearly shown in FIG. 2. The switches 56, 58, and 60 and respective trigger arms 64, 66, and 68 are preferably arranged or disposed in "stair-step" relationship and in substantial planar alignment with the dispensing member 52. The spacing between the trigger arms 64, 66, and 68 are particularly selected for a purpose as will be hereinafter set forth.

Referring now to FIG. 1, a control device generally indicated at 70 is provided for the apparatus 10, and is substantially identical with the type of control unit dis-

closed in the aforementioned co-pending application. The control device 70 may be remotely disposed with respect to the dispensing apparatus 10, or may be installed in the proximity thereof, as desired. The unit 70 depicted herein is of a modular type construction comprising a housing 72 having an on-off or key switch 74 suitably mounted thereon and provided with means for receiving a plurality of cells or modules 76, 78, and 80. Whereas the particular embodiment shown in FIG. 1 includes three modules, it will be apparent that substantially any number of modules as desired may be provided, preferably with one module for each different quantity of fluid to be delivered from the apparatus 10. Each module is electrically connected with a respective fluid dispensing micro-switch as will be hereinafter set forth.

Each of the modules 76, 78, and 80 is substantially identical and comprises and is constructed in a manner as set forth in the aforementioned co-pending application for ready insertion within the housing 72. The electrical components of each module 76, 68 and 80 are substantially identical. The off-on switch 74 is preferably of the key operated type and is suitably electrically connected with each module 76, 78 and 80 to supply electrical current thereto. Of course, the off-on switch 74 is suitably connected with a source of electrical current, such as the usual house power, as is well known, and suitable electrical connections (not shown) are preferably interposed between the switch 74 and the modules 76, 78, and 80 for converting the normal AC house power to DC power. Each module 76, 78, and 80 is provided with an on-off switch 82, 84, and 86, respectively, whereby selective operation of each modules may be provided, and a suitable pilot light 88, 90, and 92 is provided for each module 76, 78, and 80, respectively, for indicating the operation status thereof. In addition, each module 76, 78 and 80 is provided with a suitable adjustable time-counter device 94, 96, and 98, respectively, which is preferably of the type commonly known as a triac. Each module is electrically connected with one fluid dispensing micro-switch, as for example, the module 76 is electrically connected with the switch 56; the module 78 is electrically connected with the switch 58; and the module 80 is electrically connected with the switch 60. In addition, the timer-counter of each module is set at a predetermined operation sequence for timing the operation of the pump 36 in accordance with the desired quantity or volume of fluid to be delivered through the nozzle or dispensing end 52, as will be hereinafter set forth.

Referring now to FIG. 3, an electrical schematic is depicted therein particularly illustrating the electrical circuit for a control unit 72 and dispensing apparatus 10 as shown herein. As hereinbefore set forth, the switches 56, 58, and 80 are electrically connected with the modules 76, 78 and 80 respectively. Each module 76, 78 and 80 includes a hot line H, a triac line T, and a neutral line N, with each of hot lines H being connected together, each of the lines T being connected together, and each of the lines N being connected together. A suitable relay coil 100 is electrically connected to the lines H and T for activation thereby. The relay coil 100 is in suitable operation connection with a switching device 102 whereby activation and deactivation of the coil 100 causes alternate opening and closing of the switching device 102. The switching de-

vice is electrically connected with the pump motor 40 for activation thereof.

The rotor motor 30 is electrically connected to a source of electrical current, such as house power, through the usual plug 104, as is well known. In addition, a plurality of suitable outlets 106 and 108 may be provided within the housing 12 for convenience, such as for example permitting connecting of a light, or the like, for facilitating viewing the interior of the housing. A blinker lamp 110 is electrically connected with the switch 48 and is mounted in the housing or on the housing 12 in such a manner as to attract attention when energized for a purpose as will be hereinafter set forth.

In use, the apparatus 10 may be used for dispensing a substantially exact and repeating uniform quantity of the sauce 26 in accordance with the optimum quantity or volume thereof as related to the size of the pizza to be baked. The particular embodiment of the apparatus 10 depicted herein is designed and constructed for dispensing pizza sauce for pizzas of three varying sizes. The trigger arm 66 is spaced from the nozzle or dispensing end 52 a distance substantially equal to the radius of the pizza pan 112 normally utilized in the preparing and baking of a medium size pizza. The trigger arm 64 is similarly spaced from the nozzle 52 a distance substantially equal to the radius of the pizza pan (not shown) normally used for the preparation and baking of the smallest size pizza. The trigger arm 68 is spaced from the nozzle 52 a distance substantially equal to the radius of the pizza pan (not shown) normally used for the preparation and baking of the largest size pizza.

The timer mechanism of the module 76 connected with the switch 56 is adjusted for operating the motor 40 and pump 36 for a sufficient time period to deliver substantially exactly the quantity of sauce 26 considered to be the optimum for the small size pizza. Similarly, the timer mechanism of the module 78 connected with the switch 58 is adjusted for operating the motor 40 and the pump 36 for a sufficient time period to deliver substantially exactly the quantity of sauce 26 considered to be the optimum for the medium size pizza; and the timer mechanism of the module 80 connected with the switch 60 is adjusted for operating the motor 40 and the pump 36 for a sufficient time period to deliver substantially exactly the quantity of sauce 26 considered to be the optimum for the largest size pizza.

In order to operate the apparatus 10, the pizza pan 112 having the unbaked pizza dough (not shown) thereon is manually placed beneath the nozzle 52 in such a manner that the nozzle is substantially centrally disposed with respect thereto, and sufficiently below the nozzle 52 as to be in alignment with the trigger arm 66, as shown in FIG. 2. The outer periphery of the pan 112 is thus brought into engagement with the trigger arm 66 for moving the arm 66 in a direction for activating the associated micro-switch 58. This causes the module 78 to energize the relay coil 100 through the preselected time interval in accordance with the timer mechanism of the module 78. The energization of the relay coil 100 causes the motor 40 to activate the pump 36 through the presented time interval for delivery of the predetermined quantity of sauce 26 considered to be optimum for the particularly pizza pan 112. When the time interval has lapsed, the motor 40 and pump 36 are deactivated and the flow of the pizza sauce is stopped. Thus, not only is the proper quantity of sauce 26 delivered to the pan 112, but also the sauce is depos-

ited substantially in the center of the pan 112 for facilitating the even distribution of the sauce on the pizza dough. Of course, the operation is repeated with each pizza pan, with the trigger arm for the related pan size being similarly engaged for activation of the pump 36 to dispense the sauce.

The blades 34 are normally rotated continuously during use of the apparatus 10, regardless of whether or not the pump 36 is operating. This assures that the mixture or sauce within the vessel 22 is maintained substantially homogeneous at all times to assure the delivery of a high quality sauce to the pizza pans. Of course, in the event it is necessary to stop the rotation of the blades 34, such as when cleaning the apparatus 10, or replenishing the supply of sauce 26, a switch 112, which is preferably interposed between the motor 30 and the plug 104, may be utilized in the normal manner for stopping the operation of the motor 30.

When the supply of sauce 26 within the vessel 22 drops below a predetermined level or quantity, the float member 44 activates the switch 48, as hereinbefore set forth, thus causing the blinker light 110 to operate. The blinker light 110 is preferably disposed on the housing 12 in a position wherein the attention of an attendant will be attracted by the blinking light. The operation of the apparatus 10 may then be stopped in order to permit removal of the housing 12 and elements secured thereto from the position on the support 18. The supply of sauce 26 in the vessel 22 may then be replenished, or if desired the entire vessel 22 may be removed and a second vessel having a supply of the sauce 26 therein may be substituted therefor.

The cover member 14 shown herein is preferably constructed from a suitable transparent material to permit or facilitate a visual inspection of the interior portions of the housing 12.

In addition, the counter mechanism of each module counts or registers each operation of the pump 36 thereby in order that a calculation of the overall quantity of sauce delivered by each module may be achieved. Thus, an accurate account may be maintained of the amount or quantity of sauce dispensed for facilitating accounting and inventory recording.

It is usually necessary to clean out the fluid passage-way 42 at intervals for maintaining a proper operation of the apparatus 10. In order to open the flow passage-way for a continual flow of fluid therethrough without a counting of the fluid by the counting apparatus, the switch 74 may be closed for causing a substantially constant operation of the motor 40 and pump 36. During this time, the vessel 22 may either be replaced with a container of cleansing fluid, such as water, or the like, or filled with a cleaning fluid in lieu of the sauce 26. The cleaning fluid is flushed through the lines by the continual operation of the pump. The pump 36 may be continually operated in this manner until the apparatus 10 has been cleansed as desired. The switch 74 may then be opened for restoring the normal operation of the apparatus 10 as hereinbefore set forth.

It is to be noted that a switch 114 is provided in the line H between the modules and the relay coil 100. This switch is normally closed, but may be opened to cancel any accidental energizing of the switches 56, 58 or 60. For example, in the event the switch 60 has been engaged by the smallest size pizza pan, the switch 114 may be opened for preventing the delivery of the quantity of sauce normally required for the large size pizza.

Of course, any other accidental engagement of the switches 56, 58 or 60 may be cancelled by opening the switch 114. This substantially precludes accidental delivery of any sauce, and also precludes a counting of unwanted or accidentally "ordered" sauce by erroneous activation of the switches 56, 58 or 60. Opening of the switch 114 will also prevent accidental delivery of the sauce by the apparatus 10 during an interruption in the electrical supply, or the like.

From the foregoing it will be apparent that the present invention provides a novel dispenser for automatically delivering or dispensing preselected quantities of a sauce in accordance with a predetermined optimum quantity thereof for the particular use to which the sauce is to be put. For example, in the dispensing of 15 pizza sauce, the pizza pan having the unbaked pizza dough disposed therein may be disposed beneath the dispensing nozzle in such a manner as to activate the switch corresponding to the particular size pizza pan. The predetermined quantity of pizza sauce will be automatically delivered into the pizza pan with both speed and accuracy of quantity, thus permitting a uniform quality for the finished pizzas in a plurality of food preparing establishments. The novel apparatus is simple and efficient in operation and economical and durable in construction.

Whereas the present invention has been described in particular relation to the drawings attached hereto, it should be understood that other and further modifications, apart from those shown or suggested herein, may be made within the spirit and scope of this invention.

What is claimed is:

1. An automatic fluid dispensing apparatus comprising a housing disposed in substantial alignment with a stationary fluid reservoir, a rotatable shaft carried by the housing and extending into the fluid reservoir, power means provided in the housing and operably connected with the shaft for continuous rotation thereof during operation of the apparatus, an impeller provided on the outer end of the rotatable shaft and disposed in the proximity of the bottom of the fluid reservoir for agitating the fluid therein to maintain a substantially homogeneous solution, pump means disposed within the fluid reservoir and open to the fluid therein, power means provided in the housing and operably connected with the pump for selective intermittent actuation thereof, discharge conduit means connected with the pump for delivery of the fluid from the reservoir for dispensing thereof, control means operably

35
30
25
20
15

connected with the pump power means for intermittent operation thereof in predetermined time cycles for the dispensing of predetermined quantities of the fluid from the discharge conduit means, selective switching means carried by the housing and operably connected with the control means for selectively timed operation thereof whereby a variable preselected quantity of fluid is automatically dispensed through the discharge conduit in accordance with the desired quantity of fluid required.

2. An automatic fluid dispensing apparatus set forth in claim 1 and including float means disposed within the fluid, indicating means operably connected with the float means and activated by the float means to indicate a drop of the quantity of the fluid below a predetermined quantity.

3. An automatic fluid dispensing apparatus as set forth in claim 1 wherein the control means includes timing means for selective operation of the dispensing means to deliver said predetermined quantities of the fluid.

4. An automatic fluid dispensing apparatus as set forth in claim 1 wherein the control means includes counting means for facilitating the determination of the overall quantity of fluid dispensed by the apparatus.

5. An automatic fluid dispensing apparatus as set forth in claim 1 wherein the control means includes timing means for selective operation of the dispensing means to deliver said predetermined quantities of the fluid, and counting means for facilitating the determination of the overall quantity of fluid dispensed by the apparatus.

6. An automatic fluid dispensing apparatus comprising dispensing nozzle means, pump means providing communication between a fluid reservoir and the dispensing nozzle means, power means operably connected with the pump means for intermittent actuation thereof, control means operably connected with the power means for energization thereof, selective switch means operably connected with the control means for variable actuation thereof to provide said intermittent actuation, said switch means being connected with said control means for actuation thereof for operation of the pump in preselected time cycles for delivering variable predetermined quantities of the fluid through the dispensing nozzle means, and agitator means operable for stirring the fluid during operation of the apparatus.
